(57) **CLAIM**

The ornamental design for a sauna apparatus, as shown and described.

DESCRIPTION

FIG. 1 is a perspective view of a sauna apparatus showing my new design;

FIG. 2 is a front elevation view thereof;

FIG. 3 is a rear elevation view thereof;

FIG. 4 is a side elevation view thereof, the opposite side being a mirror image; and,

FIG. 5 is another perspective view thereof, with the door in an open position.

The bottom of the sauna apparatus forms no part of the claimed design.

The broken lines illustrate portions of the sauna apparatus that form no part of the claimed design; the broken lines form no part of the claimed design.

1 Claim, 5 Drawing Sheets(56)
